US0D1052818S

(12) **United States Design Patent** (10) Patent No.: **US D1,052,818 S**
(45) Date of Patent: **** Nov. 26, 2024**

(54) **IMPACT ABSORPTION PAD**

(71) Applicant: **RE-ZRO Limited**, London (GB)
(72) Inventor: **Wilhelm Marschall**, London (GB)
(73) Assignee: **RE-ZRO Limited** (GB)

(**) Term: **15 Years**

(21) Appl. No.: **29/848,567**

(22) Filed: **Aug. 3, 2022**

(30) **Foreign Application Priority Data**

(57) **CLAIM**

The ornamental design for an impact absorption pad, as shown and described.

DESCRIPTION

FIG. 1 is a front perspective view of an impact absorption pad, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines of even length depict portions of the impact absorption pad that form no part of the claimed design.

1 Claim, 9 Drawing Sheets
